**CONSTANT TORQUE-TYPE STRESS APPLIANCE
FOR FIREARM BARRELS**

Lemuel M. Temple, North Haven, Conn., assignor to Olin Mathieson Chemical Corporation, New Haven, Conn., a corporation of Virginia

Application July 12, 1954, Serial No. 442,693

4 Claims. (Cl. 42—75)

This invention relates to stress appliances in general, and to stress appliances for the bedded barrels in the stocks of firearms in particular.

It is a well known expediency to stress the barrels of firearms in order to improve their firing accuracy. This is customarily accomplished by attaching the barrels to the stocks of firearms in such manner that bending stresses are induced in them. To this end, the barrels are attached to the stocks of firearms by means of various screw-adjustable connectors which may be manipulated to vary the bending stresses in the barrels and associated stocks until optimum firing accuracy of the former is achieved. However, since the stress conditions in the usually wooden stocks will cause them to warp and, hence, change the stresses in the attached barrels induced therein with painstaking care for their optimum firing accuracy, many marksmen prefer to change the set screw-adjustments of the barrel and stock connectors of their firearms to relieve the stresses therein while the latter are not in use, and to readjust the connectors to restore the stresses in the stocks and attached barrels when the firearms are to be used again. In doing so, many marksmen count the number of full or partial turns of the adjustment screws of these connectors in stress-relieving direction when conditioning their firearms for inaction, and manipulate the adjustment screws through the same number of full or partial turns in the opposite direction when conditioning their firearms for renewed action, hoping thereby to achieve most accurate readjustment of the connectors and the restoration in the barrels of the exact stresses at which they previously fired with optimum accuracy. However, wooden stocks of firearms will in time inevitably warp to a greater or lesser extent, and even their slightest warping will defeat all attempts to restore the exact stresses in the attached barrels by the aforementioned expediency of manipulating the adjustment screws of their connectors through the same number of full or partial turns in either direction.

One prior connector of this type, shown in the patent to Brown, No. 2,497,861, dated February 21, 1950, takes warpage of a wooden stock into consideration in restoring the stresses in the attached barrel, by providing pressure screws which are threadedly received in a metal part of the stock and bear directly against the barrel. The stresses in the barrel induced therein for its optimum firing accuracy may be relieved by manipulating each of the screws in stress-relieving direction until they are disengaged from the barrel, and the same stresses may, even on warpage of the stock in the meantime, be restored in the barrel by manipulating the same screws in stress-applying direction, after their reengagement with the barrel, through the same number of full or partial turns through which they were previously manipulated in stress-relieving direction until their disengagement from the barrel. In order repeatedly to find the angular positions of these screws in which they are just disengaged from or engaged with the barrel with any degree of accuracy so

2

as to achieve by the aforementioned count of the full or partial turns of the screws the same stress condition in the barrel in each repeated instance, there is further provided in the aforesaid patented device a readily perceptible electric signal, the circuit of which is opened and closed when either screw disengages from and reengages with the barrel.

It follows from the preceding that the prior connectors of this type require for the manipulation of their adjustment screws in any event counting of the full or partial turns of the latter in order to achieve the closest possible restoration of the stress condition in a barrel in each repeated instance. However, the counting of the full or partial turns of the adjustment screw of a connector frequently gives rise to errors. Thus, errors frequently occur in manipulating the adjustment screw of a connector through full or partial turns in accordance with the established count thereof, or the established number of full or partial turns of the adjustment screw may, especially after a long time interval, be forgotten if committed to memory, or misplaced or irreparably lost if committed to writing. Also, the slightest accidental or unauthorized turning of the adjustment screw of a connector in stress-relieving position dooms to failure any attempt at restoring the same stress conditions in the barrel on subsequent manipulation of the adjustment screw through the established number of full or partial turns in stress-applying direction. Furthermore, the aforementioned Brown connector of this type, which compensates for the warpage of a wooden stock, relies for the restoration of the same stress condition in the barrel not only on the aforementioned count of the full or partial turns of the adjustment screws, but requires in addition the establishment of an electric circuit for accurate determination of the count-end and count-off points.

It is the primary object of the present invention to provide a connector of the screw-adjustment type for the stock and barrel of a firearm with a manipulator which, through the adjustment screw of the connector, relieves the stresses in the barrel and restores them therein to their exact magnitude regardless of warpage of the stock, on being turned in opposite directions, respectively, without requiring the counting of any turns in either direction or any other personal attention other than the mere physical turning of the manipulator in either direction.

It is another object of the present invention to provide for the stock and barrel of a firearm a connector of the screw-adjustment type of which the aforementioned manipulator is a wrench carried by the adjustment screw and operable to transmit to the latter unlimited torque in stress-relieving direction, and no more than predetermined maximum torque in stress-applying direction, thereby to achieve repeated relief and exact restoration of the stress condition in the barrel regardless of warpage of the stock, by the aforementioned simple expediency of turning the manipulator in opposite directions without requiring the counting of any turns thereof in either direction or any other personal attention.

It is a further object of the present invention to provide for the stock and barrel of a firearm a connector of the screw-adjustment type of which the aforementioned wrench-type manipulator is adjustable to vary the maximum torque transmittable to the adjustment screw on rotation of the former in stress-applying direction, thereby to permit the installation of connectors of this type in firearms of all kinds and subsequent stressing of their barrels for optimum firing accuracy, as well as readjustment of the stresses in any barrel if its firing accuracy should for any reason have deteriorated.

Another object of the present invention is to provide

for the stock and barrel of a firearm a connector of the screw-adjustment type of which the aforementioned wrench-type manipulator is a clutch the members of which are positively engaged to transmit unlimited torque to the adjustment screw in stress-relieving direction, and are frictionally engaged to transmit no more than predetermined maximum torque to the adjustment screw in stress-applying direction, thereby to permit harmless overdrive of the manipulator in stress-applying direction without changing the correct stress condition of the 10 barrel.

A further object of the present invention is to provide for the stock and barrel of a firearm a connector of the screw-adjustment type of which the members of the aforementioned clutch have ratchet-like teeth and cooperating pawl-like projections, respectively, and are urged into engagement with each other by a variable spring force, thereby not only achieving the aforementioned positive and frictional engagement between the clutch members for the transmission to the adjustment screw of unlimited torque and no more than predetermined maximum torque in stress-relieving and stress-applying directions, respectively, with the added assurance that the torque in stress-applying direction will, by virtue of the camming action between the ratchet teeth and pawl-like projections on the clutch members, remain constant at any adjusted magnitude for a long time, but also obtaining, when overdriving the clutch in stress-applying direction, an unmistakable signal that further rotation of the same is unnecessary, by the readily perceptible clicking sounds then caused by the ratchet teeth and pawl-like projections on the clutch members.

Further objects and advantages will appear to those skilled in the art from the following, considered in conjunction with the accompanying drawings.

In the accompanying drawings, in which certain modes of carrying out the present invention are shown for illustrative purposes:

Fig. 1 is a side view of a firearm stock-and-barrel connector embodying the present invention;

Fig. 2 is a top view of the same connector;

Fig. 3 is a longitudinal section through the connector as taken on the line 3-3 of Fig. 1;

Figs. 4 and 5 are cross-sections through the connector as taken on the lines 4-4 and 5-5, respectively, of Fig. 3;

Fig. 6 is an enlarged fragmentary section through the connector as taken on the line 6-6 of Fig. 3;

Fig. 7 is a fragmentary section similar to Fig. 6, showing certain parts of the connector in different operating positions;

Fig. 8 is a fragmentary side view of a firearm and installed connector;

Fig. 9 is a fragmentary longitudinal section through the same firearm and installed connector;

Fig. 10 is an enlarged cross-section through the firearm and installed connector as taken on the line 10-10 of Fig. 8;

Fig. 11 is a fragmentary longitudinal section through a firearm and installed connector which embodies the present invention in a modified manner; and

Fig. 12 is a fragmentary longitudinal section through a firearm and installed connector which embodies the present invention in a further modified manner.

Referring to the drawings, and more particularly to Figs. 1 to 3 thereof, the reference numeral 20 designates a stress connector having a driven member or rotary part 22 and a driving member or manipulator 24. The driven member 22 is provided at one of its ends with an axially extending shank 26 which, in the present instance, is threaded at 28 for applying stresses in a manner described hereinafter. The manipulator 24 is disposed opposite this shank, and is cup-shaped, having a bottom 30 and a rim 32 which in this instance is an-

nular and preferably knurled on its outer periphery as at 34 to serve as a convenient knob. The manipulator 24 and driven member 22 constitute the elements of a clutch, in this instance a pawl-type clutch. To this end, the bottom 30 of the manipulator 24 is provided with an annular row of ratchet-like teeth 36 (Figs. 1, 5 and 6), while the adjacent face of the driven member 22 is provided with cooperating pawl-like projections 38 which may conveniently be formed by equi-angularly notching the driven member as at 40 (see also Fig. 4). Received in the manipulator 24 within its rim 32 is the head 42 of a screw 44 having a threaded shank 46 received in the driven member 22. The blank part 48 of the shank 46 extends with a free fit through an axial bore 50 in the bottom 30 of the manipulator 24 to mount the latter on the driven member 22 for rotation coaxially of its shank 26. Surrounding the shank 46 of the screw 44 and interposed between the head 42 of the latter and the bottom 30 of the manipulator 24 is a compression type spring, in this instance in the form of opposed spring discs 52 and 54, which yieldingly hold the manipulator in driving engagement with the driven member. The screw 44 may be turned at its head 42 with a screw driver or the like in order to provide a preset compression of the spring discs 52 and 54 and, hence, the force with which the manipulator 24 is urged into driving engagement with the driven member 22.

Reference is now had to Figs. 8 to 10 which show the instant stress connector 20 installed in a firearm 60 of conventional construction, having the usual wooden stock 62 and bedded barrel 64 therein. The rear end of the barrel 64 is customarily screwed or otherwise anchored in the usual receiver (not shown) which is suitably anchored in the intermediate portion of the stock, and the barrel is further secured to the forepart 66 of the stock, in this instance by the stress connector 20. The connector 20 is adapted not only to secure the forepart of the barrel 64 to the forepart 66 of the stock, but also to induce in the barrel stresses of a magnitude to obtain optimum firing accuracy. The stresses induced by the instant connector 20 in the barrel 64 are bending stresses, and these are achieved, in the present instance, by causing the connector to draw the barrel and forepart of the stock together. In order that opposing bending stresses may be induced by the connector 20 in the barrel 64 and forestock 66, the latter is in this instance provided with a trough-like bedding recess 68 in which the barrel 64 extends with increasing clearance 70 away from the receiver.

The shank 26 of the driven member 22 of the connector 20 extends through the stock escutcheon 72 and an aligned hole 74 in the forepart 66 of the stock 62 (Fig. 9), and the threaded end 28 of this shank is received in a fixed member comprising a lug 76 on the barrel 64. The lug 76 is in this instance secured to the barrel 64 through intermediation of a band 78 on the latter. The shank 26 of the driven member 22 of the connector is provided with an annular shoulder 80 which rests against a similar shoulder 82 in the stock escutcheon 72. These shoulders form cooperating abutments whereby the barrel 64 and forepart 66 of the stock 62 will be drawn against each other to induce bending stresses in each on turning the driven member 22 in the screw-in direction of its threaded shank end 28, and these bending stresses will be relieved in the barrel and stock on turning the driven member 22 in the opposite direction, as will be readily understood.

The ratchet teeth 36 on the manipulator 24 and the pawl-like projections 38 on the driven member 22 are so arranged that the shoulders 90 of the ratchet teeth interlock with the adjacent sides 92 of the pawl-like projections (see also Fig. 6), and positively drive the member 22 in the unscrewing direction of the exemplary right-hand thread on the end 28 of its shank 26, i. e. in stress-relieving direction, when the manipulator 24 is turned

in the same direction. Accordingly, any amount of torque applied to the manipulator 24 will be transmitted to the member 22 in the stress-relieving direction to assure instantaneous relief of the stresses in the barrel and stock when the firearm is conditioned for inaction of any duration. However, on turning the manipulator 24 in the opposite or stress-applying direction in order to restore the previous stress condition in the barrel and stock for renewed use of the firearm at its optimum firing accuracy, the frictional engagement between the inclined flanks 94 of the ratchet teeth 36 and the pawl-like projections 38 (Fig. 6) will determine the maximum torque transmittable by the manipulator to the driven member 22. If the torque applied to the manipulator 24 in stress-applying direction exceeds this maximum at which the exact stress conditions in the stock and barrel for renewed optimum firing accuracy of the latter are restored, the driven member will no longer be driven and the ratchet teeth 36 on the manipulator will simply override the pawl-like projections 38 on the driven member (Fig. 7), as will be readily understood.

As already mentioned, the maximum torque transmittable by the manipulator 24 to the driven member 22 in stress-applying direction depends on the force with which the inclined flanks 94 of the ratchet teeth 36 on the former drivingly engage the pawl-like projections 38 on the latter, and this force may be varied to suit by changing the compression of the spring discs 52 and 54 by means of the adjustment screw 44. Accordingly, the barrel of any firearm may initially be stressed for optimum firing accuracy, either in the factory or by the purchaser, by manipulating the adjustment screw 44 and turning the manipulator 24 in stress-applying direction until the barrel fires with optimum accuracy, meaning that the correct stress condition in the particular barrel for its optimum firing accuracy has then been attained. A set screw 100 in the driven member 22 may then be tightened against the shank 46 of the adjustment screw 44 in order releasably to lock the latter in its correctly adjusted angular position. Thereupon, the stresses in the barrel and stock may be relieved for any inactive period of the firearm to prevent warping of the wooden stock as much as possible, by simply turning the manipulator 24 in stress-relieving direction until approximate minimum resistance to its rotation in this direction is experienced by the operator. In order to condition the firearm for renewed use, the operator or marksman need merely turn the manipulator 24 in stress-applying direction until the latter overdrives the member 22 and indicates to the operator or marksman that the correct stress conditions in the stock and barrel are restored and the manipulator 24 requires no further turning. The fact of the overdrive of the manipulator 24 is all the more unmistakably brought home to the operator or marksman by the clicking sounds caused by the ratchet teeth 36 and pawl-like projections 38 when the former override the latter.

Since the magnitudes of the stresses in the stock and barrel of the firearm depend solely on the tension in the connector 20, and since this tension is determined directly by the torque applied to the driven member 22 in stress-applying direction, it follows that the same stress conditions are exactly restored in the stock and barrel in each repeated instance regardless of warpage of the stock in the meantime, for the maximum torque transmittable by the manipulator 24 to the driven member 22 is and remains constant, despite any warpage of the stock, as long as the adjustment of the screw 44 is not changed.

The instant connector 20 is, by virtue of its variable maximum torque output in stress-applying direction, ideally suited for installation in all kinds of firearms and subsequent stressing of their barrels for optimum firing accuracy, as well as for accurately re-stressing the barrel of any firearm for renewed optimum firing accuracy

when its firing accuracy has for any reason whatever deteriorated.

While in the exemplary connector 20 described herein the ratchet teeth are provided on the manipulator and the pawl-like projections are provided on the driven member, these may obviously be reversed on the manipulator and driven member in a self-explanatory manner. Also, while the connector in the exemplary installation of Figs. 8 to 10 draws the stock and barrel of the firearm together for inducing the correct stress condition in the barrel for its optimum firing accuracy, the same connector in slightly modified form may be used in a firearm for forcing its stock and barrel apart in order to induce in the latter the correct stress condition for its optimum firing accuracy. Such a modified connector application in a firearm is shown in Fig. 11.

In this figure, the shank 26' of the driven member 22' of the connector 20' is provided with a collar 101 which abuts against the stock escutcheon 72' secured to the forepart 66' of the stock 62' by the screws 102. The end of the shank 26' of the driven member 22' is threaded at 28', in this instance in right-hand fashion, and is received by the lug 76' on the band 78' on the barrel 64'. Accordingly, the stock and barrel will be forced apart to induce in them bending stresses at which the latter will fire with optimum accuracy, when the driven member 22' is turned in the unscrewing direction of its threaded shank end 28', i. e. in stress-applying direction, while these stresses are relieved on turning the driven member in the opposite or stress-relieving direction, as will be readily understood. It further follows from Fig. 11 that the ratchet teeth 36' on the manipulator 24' and pawl-like projections 38' on the driven member are so arranged that the ratchet teeth will interlock with the pawl-like projections and positively drive the driven member on turning the manipulator in stress-relieving direction, and the ratchet teeth will override the pawl-like projections when the manipulator is turned in stress-applying direction at a torque in excess of its maximum torque which is transmittable to the driven member and adjustable in magnitude on varying the compression of the spring discs by means of the adjustment screw (neither shown).

Reference is now had to Fig. 12 which shows a further modified stress connector 20" of constant maximum torque-type installed in a firearm having a stock 62" and a barrel 64". The instant modified connector 20" distinguishes from the earlier described connector 20 by providing on the manipulator 24" and driven member 22" cooperating friction surfaces 110 and 112, respectively, which are held in driving engagement with each other by the spring discs 52" and 54" the compression of which may be varied by the adjustment screw 44". The maximum torque transmittable by the manipulator 24" to the driven member 22" in either stress-relieving or stress-applying direction is in this instance the same and its magnitude depends on the compression of the spring discs 52" and 54", as will be readily understood. On proper adjustment of the compression of the spring discs 52" and 54" by means of the adjustment screw 44", transmission from the manipulator 24" to the driven member 22" through the friction surfaces 110 and 112 of torque of the correct maximum magnitude in stress-applying direction results automatically in the barrel, as in the previous example, to bring about its optimum firing accuracy. However, when it is desired to relieve the stresses in the barrel to condition the firearm for an inactive period of any duration, it is preferable to turn the driven member 22" in stress-relieving direction on its knurled periphery 116 and thus circumvent the frictional driving connection between the manipulator 24" and driven member 22".

The invention may be carried out in other specific ways than those herein set forth without departing from the spirit and essential characteristics of the invention,

and the present embodiments are, therefore, to be considered in all respects as illustrative and not restrictive, and all changes coming within the meaning and equivalency range of the appended claims are intended to be embraced therein.

What is claimed is:

1. In a firearm, a stock part, a barrel part bedded therein; a stress connection for the stock and barrel parts comprising a member adapted for rotary mounting in one part and having a threaded portion for connection with the other part; a cupped manipulator having a bottom and a rim and being mounted for rotation coaxially of said member, said member and said bottom of the manipulator constituting the elements of a pawl-type clutch of which one element has ratchet teeth and the other element has cooperating pawl-like projections; a screw having an exposed head in the cup of said manipulator and a threaded shank extending through the bottom of the latter and received in said member; a compression-type spring surrounding the threaded shank of said screw and interposed between the head of the latter and the bottom of said manipulator, said spring urging said clutch elements into driving engagement with each other with a force variable with the adjustment of said screw, and said ratchet teeth and projections being coordinated so as to interlock with each other and positively drive said member on turning said manipulator in one direction, and to override each other on turning said manipulator in the opposite direction at a torque greater than a predetermined maximum.

2. A combination as set forth in claim 1, further comprising a set screw in said member for releasably locking said headed screw in angularly adjusted position.

3. In combination in a firearm, a stock, a barrel, a stress connection between the two for adjustably bedding said barrel in the forepart of said stock and comprising a fixed member carried by the barrel and having a threaded

5 aperture therein, a rotary part having an abutment engaging said stock, and a threaded shank passing through the latter into engagement with the threaded aperture of said fixed member whereby a bending stress is induced in said barrel in response to rotation of said part in a given direction, said part having an annular row of pawl-like projections extending axially of said shank, a rotary manipulator having axially projecting ratchet teeth adapted to mesh with the projections of said rotary part, a central axial bore extending through said manipulator, a headed screw passing freely through said bore and received in said rotary part to mount said manipulator coaxially upon said part, and compression spring means confined between the head of said screw and said manipulator for urging said ratchet teeth and pawl-like projections into engagement.

10 4. The combination in a firearm as defined in claim 3, in which said headed screw is adjustable with respect to said manipulator to preset the pressure of said compression spring means and consequently the maximum torque to be transmitted to said rotary part by said manipulator, and means in said part for locking said screw in an adjusted position.
